MECHANISM FOR DRAWING FIBERS IN
TEXTILE MACHINES

John Schofield, Rochdale, England

Application November 12, 1938, Serial No. 240,079
In Great Britain November 23, 1937

1 Claim. (Cl. 19—131)

This invention relates to mechanism for drawing fibers in textile machines and more particularly to improvements in the cradles which carry the belts of high draft apparatus for spinning and like machines.

These cradles usually comprise two lateral plates suitably connected together by transverse members and provided with U shaped or like recesses which fit over the rollers around which the belts pass at the rear and with slots to receive the non-rotatable bars or rods around which the belts pass at the front.

According to the present invention the cradle is formed in two parts the side plates of the lower part being formed with recesses to fit over the roller of the bottom belt and with slots to carry the non-rotatable bar or rod around which the bottom belt passes at the front and the side plates of the upper part being formed with recesses to receive the roller of the top belt and carrying the non-rotatable bar or rod around which the top belt passes at the front.

The invention will be described with reference to the accompanying drawing in which:

Fig. 1 is a side elevation of the cradle showing it in position, relative to the drawing rollers.

Fig. 2 is a longitudinal section thereof.

Fig. 3 is a front elevation of the cradle.

Fig. 4 is a section of the cradle on line 4—4

Fig. 1.

Fig. 5 is a longitudinal section of the upper member.

Fig. 6 is a plan thereof.

Fig. 7 is a longitudinal section of the lower member.

Fig. 8 is a plan thereof.

Fig. 9 is an elevation of the non-rotatable bar or rod carried by the lower member around which the bottom belt passes at the front.

The cradle is formed in two parts a lower member A and an upper member B.

The side walls a of the lower member A are connected together by the transverse members a¹ a² and each wall is formed with a recess A¹ to fit over the roller C of the bottom belt C¹ and a slot a³ to carry the non-rotatable bar or rod D over which the bottom belt C¹ passes at the front. The slots a³ are preferably inclined as shown to give the required inclination to the bar D. The bar D is preferably somewhat tapered as shown in Fig. 9 and is provided near one end with a recess d which engages in one or other of the slots a³ to prevent lateral movement of the bar when in position. The recess d is of such a depth that

when the bar D is in position the outer edge of the latter will lie at right angles to the walls a and parallel to the surface of the belt.

The side walls b of the upper member B are connected together by the fixed bar D¹ at the front around which the top belt E¹ passes. Alternatively they may be connected together by a suitable transverse member and be provided with slots to receive the bar around which the top belt passes. The side walls b are formed with recesses B¹ to receive the top roller E.

The lower edge b² of each side b of the upper member is bent outwards as shown in Figs. 3 and 10 so that when the two parts are assembled together the lower edge b² will fit over the top edges of the sides a of the lower member to prevent lateral movement of one member relative to the other.

Relative longitudinal movement between the two members is prevented by a projection a⁴ on the upper edges of the sides of the lower member which engage in corresponding recesses b³ in the lower edges of the upper member.

A cradle A constructed in two parts A and B as above described enables the top belt E¹ and its roller E to be removed from the machine without removing the bottom belt C¹ and roller C which facilitates cleaning of the belts and also the replacing of the belts in position in the cradle since each belt can be replaced independently of the other before the two parts of the cradle are assembled together. Moreover the top member, belt and roller can be removed from the machine for replacement without disturbing the bottom member.

What I claim as my invention and desire to protect by Letters Patent is:

A cradle formed in two parts—an upper part and a lower part—for carrying the top and bottom belts of high draft apparatus for spinning and like machines, said belts passing over a top and bottom roller respectively comprising the combination with a plate at each side of the upper part and a plate at each side of the lower part of an outwardly formed flange on the lower edge of each side plate of the upper part to fit over the upper edges of the side plates of the lower part and prevent lateral movement between the two parts, projections on the upper edges of the side plates of the lower part and corresponding recesses in the lower edges of the side plates of the upper part to receive said projections and prevent longitudinal movement between the two parts without preventing the upper part from being lifted directly off the lower part in a direction perpendicular to the line of contact of the two belts.

JOHN SCHOFIELD. 55
